Inventor

UNITED STATES PATENT OFFICE

ERNEST S. HAYNE, OF BIRMINGHAM, ALABAMA, ASSIGNOR OF ONE-THIRD TO JOHN T. LARGE AND ONE-THIRD TO C. C. HAYNE, BOTH OF BIRMINGHAM, ALABAMA

DRAFT REGULATOR

Application filed December 21, 1931. Serial No. 582,403.

For the sake of illustration, it might be stated that in locomotive draft regulators of known construction, the normal formation of the jet of steam issuing from the 5 exhaust nozzle disposed within the smoke box of the locomotive becomes distorted and takes an elongated or oval formation, with the result that certain of the boiler tubes that are not in the direct line of forced 10 draft, becomes cool which causes an uneven burning of the fire within the fire box of the boiler.

It is therefore the primary object of the present invention, to provide means whereby 15 by the area of the exhaust nozzle located within the smoke box, may be varied without any appreciable change in the general outline of the jet of steam, thereby causing an even draft through all of the tubes of 20 the boiler.

Another object of the invention is the provision of a draft regulator of this character which may be readily and easily installed, eliminating the necessity of making 25 extensive alterations in the usual nozzle construction, to apply the device.

A still further object of the invention is to provide an operating means for operating the control device, the operating means 30 controlled from a point within the engine cab, and at the will of the engineer.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made 40 within the scope of what is claimed, without departing from the spirit of the invention.

Referring to the drawings:

Figure 1 is a vertical sectional view 45 through the smoke box of a locomotive, illustrating a device constructed in accordance with the invention as applied to the exhaust nozzle thereof.

Figure 2 is a plan view of a nozzle

equipped with a regulator constructed in accordance with the invention.

Figure 3 is a vertical sectional view through the nozzle.

Figure 4 is a vertical sectional view taken 55 at right angles to Figure 3.

Referring to the drawings in detail, the reference character 5 designates the boiler of a locomotive, which is of the usual construction, the same being provided with 60 tubes 6 that extend to the smoke box 7 of the boiler.

Positioned within the smoke box is an exhaust steam nozzle 8, the steam nozzle being 65 of a diameter approximately one inch greater than the exhaust steam nozzle now in use, for purposes to be hereinafter more fully described.

Formed integral with the steam nozzle 8, are supporting members 9 that extend laterally from the nozzle, at points substantially intermediate the ends of the nozzle.

These supporting members, provide supports for the pivoted links 10, that have their inner ends disposed near the nozzle, while the outer ends thereof extend beyond the ends of the supporting members 9, where they have pivotal connection with the curved levers 11 that in turn are connected at their inner ends, with the bar 12 which extends 75 through an opening in the side of the nozzle.

The inner ends of the pivoted links 10, have pivotal connection with the curved levers 13, which are pivotally connected with the bar 14 disposed directly opposite 80 to the bar 12, and extended through an opening in the side of the nozzle, cooperating with the bar 12 in varying the area of the nozzle.

These bars 12 and 14 are substantially 85 one and one-half inches in width, with the result that when the bars are moved to the limits of their inward movements, they will contact at a point substantially centrally of the nozzle, and reduce the entire area of the nozzle by several square inches, with the result that the area of the nozzle will be approximately equal to the area of the exhaust steam nozzle now in common use.

When the bars 12 and 14 are moved to the 100

limits of their outward movements, the area of the nozzle will be increased approximately the same as by one inch increase in diameter thereby reducing the forced draft 5 caused by the steam passing through the nozzle.

An operating rod indicated by the reference character 15 connects with one end of the bar 12, and passes through an opening 10 in the wall of the smoke box, where it has pivotal connection with the bell crank lever 16, to which the rod 17 is connected, there being provided a hand lever 18 at one end of the rod 17, the lever 18 being positioned 15 within the engine cab in easy access to the engineer.

A rack 19 is provided adjacent to the lever 18, so that the bars 12 and 14 may be moved to various positions of adjustment, 20 and locked in such positions.

In the use of the device, assuming that the engine is drifting, whereupon a forced draft is unnecessary for the efficient running of the engine, the bars 12 and 14 are 25 moved to their outermost positions, thereby increasing the area of the nozzle and reduce the force of steam passing through the nozzle.

Should it be desired to increase the forced 30 draft, the bars 12 and 14 are moved inwardly to reduce the area of the nozzle and restrict the passage of steam, causing a forced draft, which is necessary on a grade wherein it is desired to generate steam rapidly.

35 Due to the construction shown and described, it will be seen that although the area of the nozzle may be decreased, the jet of steam issuing from the nozzle is circular in formation to the end that the draft 40 through the various tubes of the boiler is equal, thereby eliminating any possibility of cooling certain of the tubes of the boiler by reducing the diameter of the nozzle, as is common practice in draft regulating nozzles.

45 It might be further stated that with a device of this character, an appreciable saving in fuel is assured, and the efficiency of the locomotive greatly increased.

50 Having thus described the invention what is claimed is.

I claim:

55 The combination with the exhaust nozzle of a locomotive, said nozzle having circular openings formed in opposite sides thereof, of a draft regulator comprising bars circular in cross section, operating through the 60 openings in opposite directions and in alignment with each other adjusting the area of the nozzle, and means for operating the bars simultaneously.

In testimony that I claim the foregoing as my own, I have hereto affixed my signature.

65 ERNEST S. HAYNE.
